UNITED STATES PATENT OFFICE.

FRANK A. OWENS, OF SEATTLE, WASHINGTON.

LOCK.

No. 828,961.

Specification of Letters Patent.

Patented Aug. 21, 1906.

Application filed April 19, 1905. Serial No. 256,509.

To all whom it may concern:

Be it known that I, FRANK A. OWENS, a citizen of the United States of America, and a resident of the city of Seattle, in the county of King and State of Washington, have invented certain new and useful Improvements in Locks, of which the following is a specification.

My invention relates to improvements in locks and being particularly adapted for use in connection with latches wherein a sliding latch-bolt is embodied; and the primary object thereof is to provide improved locking means for controlling the means employed in the latch-housing for retracting the bolt.

A further object is to provide a simplified and inexpensive lock mechanism which will be exceedingly difficult to operate without the proper key.

Further objects and advantages will be set forth in the following description.

In the accompanying drawings, in which like numerals of reference indicate like parts throughout the several views, Figure 1 is a plan view of a latch, the cover-plate being removed, provided with my improvement. Fig. 2 is a section taken on line 2 2 of Fig. 1. Fig. 3 is a detail view of my improved lock with the casing thereof shown in diametrical section. Fig. 4 is a section taken on line 4 4 of Fig. 3. Fig. 5 is a section taken on line 5 5 of Fig. 3; and Fig. 6 is a diametrical section showing a key in position, the same having retracted the locking-pins, those sections of the respective barrels immediately in the rear of the key being removed.

The invention includes a casing composed of outer and inner shells 1 and 2, shell 1 being provided at its inner end with a wall which is formed with an axial opening 3, the function of which will be made apparent in the following. The inner shell 2 has its outer end formed with an outturned externally-threaded flange 4, which bears on the outer end of shell 1 and has its threads normally engaged with internal threads of a cap 5, which is threaded onto shell 1 and forms a closure for the outer end of the casing. In the forward half of this casing is placed what I term a "front" barrel 6, and in the rear half is the back barrel 7. These barrels fit rotatably in the inner shell of the casing and are each formed with a central longitudinal key-opening 8, substantially rectangular as viewed in cross-section, the opening of one barrel being adapted to register with that of the other, so

as to form a continuous keyway. Adjacent their forward and rear ends these barrels are formed with suitable transversely-disposed apertures which extend entirely therethrough, 60 and in these apertures lock pins or tumblers 9 are located. These pins 9 are formed with laterally-projecting arms 10, which fit freely in suitable slots 11, communicating with said apertures and keyway, and these arms extend across the said keyway.

The lock-pins are of suitable size to move longitudinally in the apertures and are formed equal in length to the length of respective apertures and are normally yieldingly held 70 with one end portion projecting slightly beyond the periphery of the barrels when the arms 10 rest against the walls of slots 11, which lie closest to the center of the keyway, and said pins are held in this position by 75 springs, as 12, of suitable form to allow the pins to be moved inwardly. These springs are arranged about the pins in suitable enlargements of the said apertures formed at the slots 11 and press upon the arms 10 and 80 against the end wall of said enlargements.

The barrels 6 and 7 normally rest with their respective key-openings standing at right angles to each other, (see Fig. 4,) and suitable apertures, as 14, are arranged in the 85 shell 2 to receive the projecting ends of the lock-pins when the barrels are so resting, thereby locking them from rotation. Apertures 15 are arranged to receive the opposite ends of said pins should they be shifted too far. 90

Secured to the rear end of barrel 7 and projecting through the opening 3 of the casing is a stem 17, having laterally-projecting arms or cams 18 and 18', arm 18 of which is adapted to bear on the end portion of one arm of a bell-crank lever 19, pivoted on a stud 20, secured to latch-housing 21, and the other arm of this lever bears on the forward face of a shoulder 22, formed on the shank of a latch-bolt 23. This latch-bolt 23 is slidably mounted in the housing 21 and is yieldingly held in advanced or locking position by a spring 24. When the lock is shifted to the opposite side of the housing 21, as indicated by dotted lines in Fig. 2, the arm 18' upon proper rotation of 105 the barrels will engage lug 25, secured to the inner end of the latch-bolt, and thereby retract the same. It will therefore be obvious that bell-crank lever 19 and arm 18 only operate when the lock is on that side of the 110 latch-housing, as indicated in Figs. 1 and 2.

In the construction shown (see Fig. 2) the

lock-casing 1 is threaded into one wall of the latch-housing and is secured by a screw 13. Consequently the latch-bolt can be moved only through the employment of a key from one side of the door. From the other side of door the latch-bolt is operated by the usual knob 26, the spindle 27 of which projects into the housing 21 and has secured thereon the usual roll-back 28, provided with opposite projections, which engage suitable lugs on the yoke 29. One of these lugs, as 30, is extended beyond the outer edge of the yoke, so as to engage the shoulder 31 of latch-bolt, and thereby retract the same when the roll-back is turned by rotation of said knob 26. The yoke is slidably mounted on a suitable guide 32 and is returned to its normal position after each movement thereof by means of a spring 33.

Numeral 34 indicates a pivoted catch of usual form, which can be operated from the edge plate 35 of the housing, so that its inner end will be swung into engagement with the forward face of shoulder 22, and thereby hold the latch-bolt in retracted position.

The knob-spindle 27 and the lock-casing are both removable, so that they can be arranged on either side of the latch-housing, as indicated by full and broken lines in Fig. 2, it being obvious it is desirable that the key-controlled means should always be at the outer side of the door, so that entrance to the house can only be effected through the intermediary of a key.

Each barrel is formed in four longitudinal sections, (indicated at *a*, *b*, *c*, and *d*), so that the lock-pins and their springs can be properly placed in position, and the sections are secured together by suitable means, as screws 36.

The upper arm of bell-crank lever 19 and the lug 30 of yoke 29 are unattached to the latch-bolt 23, so that the latch-bolt will operate inwardly independently thereof when the door is being closed.

The key 37, employed to open this lock, is of suitable form to fit in the keyway of the barrels 6 and 7 and is provided with notches 37' on its opposite side edges of the forward half, as shown, which receive the arms 10 on the lock-pins in the front barrel 6 and hold these pins from engagement with the shell 2. The forward barrel is then free for rotation and is turned a quarter of a turn in the direction of arrow A, Fig. 4, by turning the key to bring the key-opening into alignment with the key-opening in the rear barrel 7. The key is then pressed inward, and the notches 37" in the forward half of the key serve to operate the lock-pins in the rear barrel, while the projections 37''' in the rear half of the key hold the lock-pins in the front barrel disengaged from the casing during this movement, as illustrated in Fig. 6. When the key is seated properly in the keyway, both barrels

are rotated by turning the key reversely, as indicated by the arrow B, Fig. 4, and thus latch-bolt 23 is drawn to retracted position. This reverse movement returns the front barrel to normal position, and the key can then be withdrawn, and spring 24 will reset the rear barrel to its normal position. The notches 37' and 37''' are obviously the same in order that they both will serve to retract the lock-pins of barrel 6. Notches 37" are different, however. Therefore the lock is made more difficult to operate by a person who is not provided with the proper key.

If the lock-pins should be moved too far by a key, the opposite ends thereof will be brought into engagement with the openings 15, and thus prevent rotation of the barrel, and even should they be properly moved to allow the front barrel 6 to be turned those pins in barrel 7 will also have to be properly retracted, and so held before both barrels can be simultaneously rotated.

Having thus described my invention, what I claim as new, and desire to secure by Letters Patent of the United States of America, is—

1. A lock comprising a casing, rotatable barrels mounted therein and being formed with key-openings, the said key-openings being normally out of registration, transverse lock-pins slidably mounted in said barrels, means normally forcing said pins into locking engagement with the casing, and means actuated from said key-openings for retracting said lock-pins.

2. A lock comprising a casing, a plurality of barrels formed with key-openings and transverse apertures extending entirely through the barrels, the key-openings in said barrels being normally out of registration, said casing having apertures arranged at the opposite end of the apertures of said barrels, spring-pressed lock-pins mounted in the apertures of the barrels and having one of their ends normally projected and engaged in the adjacent apertures of the casing, the opposite apertures of the casing being adapted to receive the opposite ends of said pins, and arms secured to said lock-pins and projecting into said key-openings.

3. A lock comprising a casing composed of inner and outer shells, means securing said shells together, said inner shell being formed with apertures, barrels rotatably mounted in the inner shell, said barrels being formed with key-openings adapted to register, but being normally out of registration, spring-pressed lock-pins mounted in said barrel, said lock-pins normally projecting into the apertures of said inner shell, and means carried by said lock-pins and controlled from said key-openings for retracting said lock-pins.

4. A lock comprising a casing, barrels formed with longitudinal openings forming a

keyway, said longitudinal openings in the barrels being normally out of registration, transverse lock-pins movable entirely through the barrels, springs for normally projecting said lock-pins beyond the periphery of said barrels, said casing being formed with apertures into which the projecting ends of said lock-pins are normally engaged and apertures into which the opposite ends of said lock-pins are movable when said lock-pins are retracted too far, and arms carried by said lock-pins and projecting into said keyway.

5. In combination with the latch-housing and the bolt slideable therein, a lock-casing constructed to be attached to either side of

said housing, a key-operated rotatable barrel in said casing, two devices in said housing operatively connected to said bolt, and means on said barrel for operating said devices to retract the bolt, said devices being arranged so that one will be operated by said means when the lock-casing is at one side of the housing, and the other operated by said means when the lock-casing is at the other side of said housing.

10. Signed at Portland, Oregon, this 20th day of March, 1905.
